R. GIRAUDIAS.
BOW FASTENER.
APPLICATION FILED MAY 10, 1920.

1,348,795.

Patented Aug. 3, 1920.

Inventor:
Raoul Giraudias
By William Clinton
Attorney

UNITED STATES PATENT OFFICE.

RAOUL GIRAUDIAS, OF MONTREAL, QUEBEC, CANADA.

BOW-FASTENER.

1,348,795.

Specification of Letters Patent.

Patented Aug. 3, 1920.

Application filed May 10, 1920. Serial No. 380,142.

To all whom it may concern:

Be it known that I, RAOUL GIRAUDIAS, a subject of the King of Great Britain, residing at Montreal, Province of Quebec, Canada, have invented certain new and useful Improvements in Bow-Fasteners; and I do hereby declare that the following is a full, clear, and exact description of the invention, such as will enable others skilled in the art to which it appertains to make and use the same.

The present invention relates to bow fasteners adapted for fastening bows of hair ribbon, portière ropes and the like.

15 An object of the present invention is to provide a simple and inexpensive fastener of this character which will securely retain the bow in place and one which will give a neat appearance to the bow to which it is applied.

With the above and other objects in view which will hereinafter appear as the description continues, the invention consists of the novel features of construction, combination and formation of parts as will be hereinafter more fully described and particularly pointed out in the appended claims.

In the accompanying drawings:

30 Figure 1 illustrates the fastener as applied to a hair ribbon;

Fig. 2 also illustrates an application of the fastener when applied to the ropes of a curtain;

35 Fig. 3 is a rear elevation of the fastener;

Fig. 4 is a perspective view of the same;

Fig. 5 is a transverse section; and,

Fig. 6 is a section through the fastener at right angles to Fig. 5, illustrating how 40 the cloth of the bow may be connected thereto.

Referring now more particularly to the accompanying drawings wherein like and corresponding parts are designated by similar reference characters throughout the several views,

The fastener embodying the present invention comprises a circular plate or ring 1 having a central opening 2 and being concaved, as better illustrated in Figs. 5 and 6. Formed with the edges of the ring 1 and arranged diametrically opposite are the strips or projections 3 which may be curled upon themselves to form the bearings as shown, 55 and pivotally supported within each bear-

ing is a ring or loop 4. These projections 3 are each provided with an opening in which may be seated the reduced ends 5 of a leaf spring 6. This leaf spring 6, as illustrated in Fig. 4, may have a plurality of 60 openings therein so that it may be secured to the bow by means of stitching and the like. This leaf spring 6 is made from a flat strip of spring steel and is slightly greater in length than the distance between the projections 3, so that when the leaf spring is placed in position, it will assume a convex configuration, as better illustrated in Fig. 5, but when applying pressure to the medial portion of this leaf spring, it may be forced 65 inwardly to assume the position as shown in dotted lines in Fig. 5, where it will assume a concave configuration and extend substantially parallel with the concave inner face of the ring 1 whereby the bow 9 70 may be gripped between the spring 6 and the inner face of the ring 1. In applying this fastener for retaining a hair ribbon bow in place, the ring 1 is placed over the knot of the bow and the leaf spring extends 75 over the rear face thereof. By applying pressure to the leaf spring, it will assume the position as indicated in dotted lines in Fig. 5, thereby gripping the bow and holding the same in place. The knot of the bow 80 may project through the opening 2 of the ring so that the knot thereof may be displayed. When using this fastener for retaining bows of hair ribbon and the like, the loops 4 may be eliminated, but when using 85 this fastener for connecting the ends of ropes or cords of portières and similar draperies, the ends of the cords 10 may first extend through the loops 4 and then be retained between the leaf spring 6 and the 90 plate 1.

Having thus fully described my invention, what I claim as new and desire to secure by Letters Patent is:—

1. A bow fastener of the character described, comprising a concave convex ring, projections formed with the outer edges of said ring, and a leaf spring adapted to be retained between said projections whereby the bow may be retained between said leaf 105 spring and the concave face of said ring.

2. A bow fastener of the character described, comprising a ring of a concave convex configuration, said ring having a central opening, extensions formed with the outer 110

edges of said ring and adapted to be rolled upon themselves to form a pair of diametrically opposite bearing lugs, loops secured to said bearing lugs, said bearing lugs having openings therein, a leaf spring, reduced end portions formed with said leaf spring and adapted to be inserted within said bear-

ing lugs, and the enlarged portion of said leaf spring being of greater length than the distance between said leading lugs, substantially as and for the purpose specified. 10

In witness whereof I have hereunto set my hand.

RAOUL GIRAUDIAS.
